CRUCIBLE FURNACE

Raymond D. York, University, and Charles M. Walker, Charlottesville, Va., assignors to Raymond D. York, trustee

Application September 30, 1940, Serial No. 359,114

13 Claims. (Cl. 263—11)

This invention relates to crucible furnaces, and more particularly to a forced draft furnace of the coke-fired type.

For many years, coke-fired crucible furnaces have been displaced by other types of furnaces such as oil fired and electric furnaces because of many advantages which were considered to reside in the latter, even though coke-fired furnaces are lower in cost and more economical to operate. It has been found in recent years that later types of furnaces have a substantial percentage of failures in providing metals for many different uses.

An important object of the present invention is to provide a furnace which possesses the advantages of a coke-fired furnace as to cost of manufacture and economy in the production of metal and which, because of the high temperatures and uniform heats which it provides has been found to very materially reduce the percentages of failures in producing metal for many different uses.

A further object is to provide a furnace of the coke-fired type wherein the air for supporting combustion is preheated in a novel manner, thus assisting in maintaining high temperatures within the furnace.

A further object is to provide a coke-fired furnace of the type referred to wherein the absorption of heat into the air fed through the grate is utilized for maintaining at lower temperatures the portions of the furnace walls which are ordinarily most highly heated, thus greatly lengthening the life of the furnace.

A further object is to provide a furnace of the type referred to wherein the walls of the furnace are provided with novel preheating ducts for heating the air which supports combustion, and wherein the location, structure and functioning of the ducts is such that the air passing therethrough maintains the normally hottest portions of the furnace wall at uniformly lower temperatures to minimize the burning-out of such portions of the furnace walls, thus greatly lengthening the life of the furnace.

A further object is to provide a metal jacket around the furnace and to provide novel means for assembling the insulating and fire brick elements within such jacket to form the fire box of the furnace.

A further object is to provide, in conjunction with the preheating ducts referred to within the furnace wall, an auxiliary duct surrounding the metal jacket of the furnace in such a manner as to initially absorb heat therefrom so as to pass

air into the interior heating ducts at a temperature higher than room temperature.

A further object is to provide, in conjunction with a furnace of the type referred to, a novel form of crucible supporting block wherein a portion of the air for supporting the combustion of the fuel passes through ducts in the supporting block to tend to carry heat away from the block itself to lengthen the life thereof, the air passing through the block absorbing heat units from the block to assist in maintaining the latter at a lower temperature.

A further object is to provide in conjunction with the block structure novel means for supporting the grate and the crucible supporting block and to supply to the latter the desired air for passage through the openings therein.

Other objects and advantages of the invention will become apparent during the course of the following description.

In the drawings we have shown one embodiment of the invention. In this showing—

Figure 1 is a central vertical sectional view through the furnace, taken on a plane indicated by the line 1—1 in Figure 2.

Figure 2 is a horizontal sectional view on line 2—2 of Figure 1.

Figure 3 is a similar view on line 3—3 of Figure 1.

Figure 4 is a sectional view taken arcuately as indicated by the line 4—4 in Figure 3, and,

Figure 5 is a fragmentary vertical sectional view taken on line 5—5 of Figure 2.

Referring to Figure 1 the numeral 10 designates

35 the base of the furnace, which is cast relatively heavy as shown, and is preferably provided with a depending annular flange 11 to support the base on the surrounding surface 12. The base is pro-

vided with a central frustro-conical supporting portion 13 having a flat circular top 14 from

40 which an annular flange 15 projects upwardly, this flange being slightly smaller in diameter than the top portion 14. The top portion 14 supports a tubular column 16, the lower end of which fits over the flange 15 to maintain it properly centered with respect to the furnace. The column 16

45 is provided with air inlet openings 17 for a purpose to be described.

The furnace further comprises a cylindrical shell 18 the lower end of which fits downwardly over the flange 11, as shown in Figure 1. Within the shell 18 is arranged a horizontal shelf member 19 suitably supported by radially inwardly projecting bracket elements 20 welded or otherwise secured to the shell 18. These brackets are

arranged at spaced points around the furnace, as will be understood. The shelf 19 is arranged a substantial distance above the base 10 to provide an air or draft chamber 21. The shelf 19 is of a diameter approximately equal to the internal diameter of the shell 18 to fit therewithin.

The shelf 19 is provided with a central circular opening 22 and the upper surface of the shelf around such opening supports the peripheral portion of a grate 23. The grate is provided with a central circular opening 24 which tapers to decrease in diameter upwardly, and the inner peripheral portion of the grate rests upon and is supported by a plate 25 resting upon the upper end of the column 16 and provided with a depending annular flange 26 fitting within the upper end of the column 16. The plate 25 is provided with a central opening 27 for the passage of air upwardly therethrough.

A crucible 28 is adapted to be arranged in the furnace and to be supported by a block indicated as a whole by the numeral 29. This block is preferably formed as described and claimed in our copending application Serial No. 272,658, filed May 9, 1939. The block comprises a permanent element 30 and a replaceable element 31, the lower portion of the permanent element resting upon the plate 25 to be directly supported thereby and having its outer surface tapered to correspond to the taper of the opening 24 to fit therein, as shown in Figure 1.

The replaceable block element 31 is provided with an axial tapered opening 32 which surrounds a similarly tapered portion 33 formed integral with the block element 30 and projecting upwardly therefrom, the diameter of the upper end of the portion 33 being slightly less than the internal diameter of the lower end of the opening in the block element 31 to permit the assembly of the elements. In assembling the elements of the block structure, a layer of material 34, such as paper, is arranged around the upwardly projecting portion 33 of the block 30 and over the upper face of the body portion of such block element. The block element 31 is then placed in position and the space between the surface of the opening 32 and the adjacent layer of paper 34 is filled with a suitable cement as indicated by the numeral 35.

The permanent block element 30 is provided in the bottom thereof with a recess 36 communicating with the opening 27, and the walls of the block element 30 are provided with upwardly inclined openings 37 extending therethrough and preferably decreasing in cross-sectional area radially outwardly of the block, as shown in Figure 1. These openings feed air to the fire bed around the block and serve the two purposes of assisting in the combustion of the fuel and in maintaining the block structure at relatively lower temperatures than ordinarily would occur, thus tending to substantially lengthen the life of the block structure.

A circular casing 38 surrounds the furnace outwardly of the draft chamber 21 to form a pre-heating chamber 39 which preferably extends somewhat above the horizontal level of the shelf 19, as shown in Figure 1. The preheating chamber serves several purposes, for example, in pre-heating the air, protecting workmen from possible injuries from burns by coming into contact with the bottom portion of the furnace, and in improving the supplying of the air to the furnace to support combustion. The casing 38 may be

welded or otherwise secured in position around the shell 18.

An inlet opening 40 is provided in the casing 38 and receives air from the blower 41 of any suitable type. As will become apparent, the air divides upon being pumped through the opening 40 and passes circumferentially through the chamber 39 to the opposite side of the furnace, whereupon it passes through an opening 42 formed in the shell 18, it being apparent that the openings 40 and 42 are preferably diametrically opposite each other. The cross-sectional continuity of the chamber 39 is interrupted to permit the cleaning out of ashes from the ash pit or draft chamber 21 and to render uniform the flow of air around the chamber 39 at the desired velocity. As shown in Figure 4, the shell 38 is provided with upper and lower walls 43 and 44, the former of which is continuous around the furnace at all portions of such wall lying in a horizontal plane. The wall 44 is offset upwardly to one side of the opening 42, as at 45, to provide space for a clean-out door 46 which is accessible for the cleaning out of the ash pit.

The offsetting of the bottom wall 44 as at 45 obviously restricts the flow of air around the chamber 39 and this is desirable in order to maintain an ample volume of air in the chamber 39 a sufficient length of time to permit proper preheating while permitting a sufficiently rapid flow of air to and through the opening 42 to the furnace. In fact it has been found desirable to add a baffle 46 adjacent one vertical wall of the offset 45 to somewhat further impede the passage of air through the space 47 above the offset 45.

The offset 45 and baffle 46 obviously retard the flow of air to the opening 42 from one side thereof and it is desirable to provide means at the opposite side of the opening 42 to similarly retard the flow of air to the opening 42 to equalize the flow of air passing to this opening from opposite sides thereof. To this end, a vertical baffle 48 is arranged adjacent the opening 42 and extends from the top wall 43 to a point spaced from the bottom wall 44 to provide a somewhat restricted passage 49. A horizontal baffle 50 is arranged at a point spaced from the top wall 43 to provide a somewhat restricted passage 51, and one end of the baffle 50 is spaced from the baffle 48 to provide a somewhat restricted passage 52. The opposite end of the horizontal baffle 50 is connected to a vertical baffle 53 the upper and lower ends of which are spaced from the top and bottom walls 43 and 44 respectively to provide restricted passages 54 and 55. With the construction shown, there will be a properly retarded flow of air at a uniform rate to the opening 42 from both sides thereof while permitting free access to the ash pit.

The structure built up within the shell 18 to provide the fire box of the furnace is of particular importance. The fire box proper is formed of a plurality of high grade refractory bricks 56 laid to provide a cylindrical fire box forming the lower portion of the combustion chamber 57. The refractory bricks 56 may be of the type having lug and recess or tongue and groove engaging faces as indicated by the numeral 58.

The lowermost layer of the fire bricks 56 rests upon a fire brick structure indicated by the numeral 59. Such structure rests directly upon and is supported by the shelf 19 and is constructed of a plurality of fire bricks laid so as to form a circular unit the diameter of the opening

60 of which is somewhat greater than the diameter of the opening 22 to allow sufficient space on the upper surface of the shelf 19 to support the grate 23. The radially outer surface of the fire brick unit 59 is circular, which is also true of the cross-sectional shape of the shell 18. However, it is impossible in practice to make both of these units true circles and in assembling the structure, there would be undue pressure caused by the shell 18 against the fire brick structure 59 if the latter were made of such size as to fit tightly within the shell 18. To eliminate such difficulty the outside diameter of the fire brick unit 59 is made appreciably smaller than the internal diameter of the shell 18 and after the fire brick unit 59 has been located in position, the space between such unit and the shell 18 is rammed with crushed fire brick and high temperature cement, as indicated by the numeral 61.

The fire brick unit 59 is provided approximately in the axial plane of the opening 42 with an air inlet opening 62 of substantial size as shown in Figure 3, and such opening is in registration with an opening 63 of similar shape and size formed in the shelf 19. A casing 64 is arranged beneath the shelf 19 to connect the opening 42 to the opening 63, the air passing through the opening 42 thus passing upwardly through the openings 62 and 63 without flowing into the draft chamber or ash pit 21. Diametrically opposite the opening 62, the fire brick unit 59 is provided with a pair of openings 65 having a block 65' (Figure 5) therebetween, and the openings 65 register with openings 66 of similar shape and size formed in the shelf or plate 19 to discharge air into the draft chamber 21 in a manner to be described.

Radially outwardly of the lowermost fire brick 56, a plurality of insulating bricks 67 is laid in circular form against the inner surface of the shell 18 and defining with the lowermost row of fire bricks 56 an annular air passage 68 communicating at one side with the opening 62 and at the opposite side with the openings 65. The circumferential continuity of the passage 68 is broken by a block 68' for a purpose to be described. Thus it will be apparent that air flowing upwardly through the opening 62 will circulate around the lowermost row of fire bricks 56 and thence downwardly through the openings 65 and 66. In view of the fact that the annular chamber 68 is arranged within the bricks 67, the latter need not define a circle smaller in diameter than the internal diameter of the shell 18, since the bricks 67 are capable of whatever slight horizontal movement is necessary to adjust its shape to that of the shell 18.

Above the insulating bricks 67 another layer of insulating bricks 69 is laid, and such layer of bricks has its radially inner and outer surfaces respectively circular in form except that the structure as a whole is provided at diametrically opposite points respectively with an opening 70 and a pair of openings 71, formed in the inner periphery of the structure, to communicate with the annular passage 68, the openings 71 being separated by a block 71'. Since the structure made up of the fire bricks 69 cannot shift horizontally to accommodate its outer periphery to the shape of the shell 18, its outside diameter is made smaller than the internal diameter of the shell 18 to provide an annular space which, after the bricks 69 have been assembled in position, is filled with a mixture of crushed fire brick

5 and high temperature cement 72, similar to that employed around the fire brick structure 59. For a purpose to be described, the opening 70 is preferably approximately one-half the area of the opening 62, and the sum of the areas of the openings 71 is slightly greater than the area of the openings 65.

10 Above the fire bricks 69 a series of insulating bricks 73, similar to the bricks 67, is laid up within the shell 18, a single circumferential series of the bricks 73 being arranged with their radially outer surfaces in contact with the shell 18. The series of bricks 73 has its radially inner surface spaced from the adjacent fire bricks 67 to form an annular space or chamber 74 similar to the space 68. The space 74 being annular, the bricks 73 are free to shift horizontally to accommodate themselves to the shape of the shell 18, and no space need be left between the bricks 73 and the shell 18. The space 74 communicates at one side with the opening 70 and diametrically opposite such opening a block 73' is arranged above the block 71' for a purpose to be described.

15 Above the bricks 73 another layer of fire bricks 74' is laid in circular form with the inner periphery thereof contacting with the outer periphery of the adjacent series of fire bricks 56. The bricks 74' are similar to the bricks 69 except that no gaps are left therein for openings, the bricks 74' forming a solid horizontal structure defining the top of the passage 74. Since the bricks 74' are incapable of shifting horizontally to accommodate themselves to the shape of the shell 18, a space is left between the bricks 74' and shell 18 to be referred to later.

20 25 Above the bricks 74' a solid circular layer of insulating bricks 75 is laid, the radially inner surface of the series of bricks 75 contacting with radially outer surfaces of the adjacent fire bricks 56. A space is left between the radially outer surfaces of the bricks 75 and the shell 18, as in the case of the bricks 74'. The upper surfaces of the bricks 75 and the upper surfaces of the uppermost layer of bricks 56 preferably lie in a common plane.

25 30 Above the bricks 56 and 75 several circular layers of fire bricks 76 are laid up, the lowermost layer of such bricks extending across the uppermost bricks 56 and across a substantial portion of the bricks 75, as shown in Figure 1. Accordingly the bricks 76 tend to bind the bricks 56 and 75 together. At least for a portion of the height of the bricks 76, a circular series of insulating bricks 77 is laid up as shown in Figure 1 to minimize passage of heat radially from the upper portion of the combustion chamber. These bricks have their radially outer surfaces spaced from the shell 18. After the assembly of the elements above the bricks 73, a mixture of crushed fire brick and high temperature cement 78 is rammed into the spaces radially outwardly of the bricks 74', 75 and 77 and above the latter bricks to the upper limits of the shell 18 and the uppermost bricks 76. The assembly of these elements completes the furnace except for the top thereof which may be of any suitable structure (not shown) such, for example, as the structure shown in our copending application Serial No. 272,658, referred to above.

35 40 The operation of the apparatus is as follows:

45 Assuming that a crucible 28 is arranged in the furnace surrounded by a bed of burning coke, the combustion of the coke will be supported by air pumped by the blower 41. This blower pumps air into the chamber 39 at the right hand side

of the apparatus as viewed in Figures 1 and 2, the air dividing and flowing in opposite directions through the chamber 39. The air, in passing around the chamber 39, will absorb heat from the ash pit 21, thus preheating the air while at the same time providing protection for workmen around the furnace, preventing their being burned by contact with the lower end of the furnace. For example, workmen's hands will strike the casing 38 in some instances, as when shoveling ashes from the ash pit through the clean-out door 46.

It is desired to maintain a substantial volume of air in the chamber 39 and to move this air relatively slowly to permit it to take full advantage of the heat units present in the adjacent portion of the shell 18. The baffle means shown in Figure 4 extends around approximately half the circumference of the chamber 39 and the structure of such baffle means is such as to provide access to the clean-out opening 46 while at the same time retarding the flow of air to the inlet opening 42. Free flow of air is impeded on one side of the opening 42 by the structure 45 and baffle 46, and is impeded to an equal extent on the opposite side of the opening 42 by the baffles 48, 50 and 53. While these baffles provide air passages exceeding in cross-sectional area the area of the opening 42, they none the less impede the free flow of air more than if they were eliminated, and the air permitted to flow directly to the opening 42, the direct flow of air being interrupted and eddy currents being set up as will be apparent.

Air entering the opening 42 flows through the casing 64 and thence upwardly through the opening 62 (Figures 1 and 3). The opening 70 has an area of approximately one-half the area of the opening 62. Thus the opening 62 admits sufficient air for circulation through both of the annular passages 68 and 74, and the relative areas of the openings 62 and 70 are such that one-half of the air flowing through the opening 62 will flow through the opening 70 and thus through the annular passage 74. The remaining one-half of the air will flow through the annular passage 68.

The air flowing through the passages 68 and 74 absorbs heat from the elements forming such passages, and particularly from the adjacent fire bricks 56, thus the air becomes elevated to a higher temperature and the absorption of heat units from the fire bricks 56 maintains such bricks at a lower temperature than otherwise would be present. The preheating of the air in this manner assists in maintaining a high temperature in the fire bed, as will become apparent, and the absorption of heat units from the fire bricks 56 greatly lengthens the life of these elements, the fire bricks lasting much longer periods of time without replacement because of the operation referred to.

The air passing upwardly through the opening 70 divides and flows in opposite directions through the passage 74. It will be obvious that the air flowing in opposite directions around the passage 74 would meet at a point diametrically opposite the opening 70, if the passage 74 were continuous. It has been found that with such arrangement, however, the meeting, surging and eddying of the air sets up such resistance to the flow of air as to require substantial pressure for pumping air through the system. Accordingly the block 73' is arranged diametrically opposite the opening 70 to stop and direct downwardly

the flow of air through each half of the passage 74, this arrangement greatly reducing resistance to the flow of the air. It will be noted that the openings 71 are separated from each other by the block 71' which is equal in thickness to the block 73'. The air from the opposite sides of the passage 74 thus flows downwardly through the openings 71. These openings are preferably equal in area and the sum of their areas is equal to and preferably slightly greater than the area of the opening 70 to take care of the expansion of the air occurring through the flow thereof around opposite sides of the passage 74.

Thus the air passing around the chamber 74 in opposite directions is directed downwardly for discharge through the openings 65 with the air flowing around the annular passage 68. The ends of the passage 68 are blocked off as at 68' diametrically opposite the opening 62 for the same reason that the corresponding portion of the passage 74 is blocked off, namely, to prevent the generation of air resistance by directing the flow of air downwardly from the ends of the passage 68 through the openings 65. The openings 65 are preferably identical in shape and size and the sum of the areas of the openings 65 preferably exceed the area of the opening 62 to take care of expansion of the air passing around the passages 68 and 74, all of this air being discharged into the ash pit through the openings 65.

The air entering the chamber 21 will be highly heated by the means referred to and is ready for passage upwardly through the fire bed. Most of the air in the chamber 21 flows upwardly through the grate 23 and through the coke burning in the combustion chamber. Some of the air in the chamber 21 enters the tubular support 16 through the openings 17 and blows upwardly through the opening 27 and into the chamber 36 to be discharged upwardly and radially outwardly through the openings 37 in the lower block element 30. The air flowing through the openings 37 is not only employed for assisting in supporting the combustion of the fuel but also serves to lengthen the life of the block 30. This is accomplished in two ways. While the preheated air is at a relatively high temperature, it obviously passes through the opening 37 at a lower temperature than the block 30 and accordingly tends to maintain this block element at a lower temperature. In the second place, the flow of air tends to carry the heat of combustion away from the supporting block and thus assists in maintaining the supporting block at a lower temperature than otherwise would be present.

With the structure shown and described it has been found that the supplying of the preheated air enables the combustion to take place at a higher temperature than is true when cold air is introduced through the grate, and accordingly higher temperatures may be maintained at a relatively uniform point. The intense heat and uniformity of the temperature permits the melting of the metal in a shorter length of time and improves the quality of the metal by greatly improving its degree of uniformity. It has been found that metal melted in the present furnace is of such quality that the percentage of rejected castings made therefrom is very greatly reduced.

The higher temperatures maintained in the furnace ordinarily would tend to shorten the life of the fire bricks, but the utilization of the chambers surrounding the fire bricks in the zone of the highest combustion temperature has been found to lower the temperature of the fire bricks to

such a point that the life of these elements is very materially increased. The passage of the air around the baffle structures in Figure 4 and through the various openings and passages of the furnace wall structure tends to retard the rate of flow of the air, but such flow is sufficient to provide ample air for supporting combustion and in practice substantially complete combustion takes place. It is obvious that the structure provides material advantages over prior constructions and the design, cross-sectional area, etc., of the various air passages is such that a relatively small blower 41 will maintain an ample flow of air for supporting the combustion of the fuel.

It will be noted that the grate 23 is not forced to support the weight of the block 29 and the crucible and its contents. Such weight is directly supported by the block 29, plate 25 and pedestal 16. The grate is called upon to support only the weight of the bed of fuel and the grate, in turn, is effectively supported by the shelf or plate 19 and by the plate 25. This feature, per se, forms no part of the present invention, being generally similar to the structure described and claimed in our copending application Serial No. 272,658, referred to above.

The pending application referred to also describes and claims the feature of the frustroconical engaging face of the block element 30 and the grate whereby the removal of the crucible is facilitated without the block 29 adhering thereto, the engaging faces of the block and grate preventing upward movement of the block. The copending application referred to also discloses the provision of a two-part block 29 with the use of the paper or similar material 34 which, under the influence of the heat in the combustion chamber, is quickly reduced to finely divided carbon. The layer of cement 35, however, prevents the block element 31 from moving upwardly with the crucible upon removal of the latter, a dovetail connection between the two block elements being maintained after the paper layer 44 has been burned. The portion of the block represented by the element 31 is subjected to the heaviest damage from heat and when burned beyond usefulness it may be broken and removed, whereupon a new element 31 may be placed in position without renewing the entire block.

The block structure shown is an improvement over that disclosed in our copending application since it provides the air passages 37 which serve to lengthen the life of the block element 30 by the absorption of heat units therefrom and by tending to blow the heat of combustion away from such block element.

The use of the steel jacket 18 provides a much stronger furnace construction and its use is made possible from a practical standpoint by the use of the block elements 59, 69, 74', 75 and 77 which are spaced inwardly from the shell 18 and with the space filled with the mixture of the crushed fire brick and high temperature cement. With the use of such construction it is not necessary that the outer surfaces of the layers of bricks which extend from the fire bricks 56 to the shell 18 be truly circular in order to fit within the shell 18, and uneven pressures which would occur through an effort to fit the brick elements within the shell 18 are eliminated, thus further increasing the life of the bricks by the elimination of internal strains.

The provision of the air passages 68 and 74 and their arrangement with respect to the asso-

ciated elements of the furnace provide greatly improved results and also lengthen the life of the furnace. The provision of two passages 68 and 74 instead of one passage is advantageous for the reason that in actual practice it has been found that the provision of a single passage of sufficient cross-sectional area to carry the necessary flow of air leaves the lower fire bricks 56 unsupported radially outwardly thereof with the result that such fire bricks will buckle during the operation of the furnace. By dividing such passage into the two passages 68 and 74, with the arrangement shown, it will be apparent that every fire brick 56 in the furnace is supported radially outwardly thereof by the outer blocks 59, 67, 69, 73, 74' or 75. Thus the fire bricks 56 are all braced against radially outward buckling.

In experimental work in connection with the furnace it was naturally assumed that it would be advisable to extend preheating passages, such as the passages 68 and 74, throughout the height of the furnace. In actual practice this was found to be wholly impracticable. The result of using such construction was that the air absorbed so much heat from the inner fire brick structure as to prevent the generation in the fire box of sufficient heat for heating the metal in the crucible. In addition, this absorption of heat was so great that the temperature of the air reaching the grate resulted in the burning out of the grate in a relatively short period of time. The use of the passages 68 and 74 adjacent the lower portion of the fire box is highly advantageous for the reason that it absorbs only so much heat as is necessary to protect the fire bricks 56 from burning out rapidly as is usually true, and in the second place results in the preheating of the air to a sufficiently high temperature to assist in the proper maintenance of combustion in the fire box without the air being sufficiently highly heated to burn out the grate.

As a result of the features referred to the highest temperature of combustion occurs at the lower end of the fire box and accordingly the crucible will be most highly heated adjacent the bottom thereof. This is a highly desirable result which is not obtained with other crucible furnaces and is the reason why higher quality metals are obtained. Instead of providing for the highest temperature adjacent the upper portion of the crucible, resulting in occluded gases and impurities in the metal in the bottom of the crucible, the present construction provides, in effect, a boiling action from the bottom of the crucible which results in the constant agitation of the entire mass of metal in the crucible with the driving off of gases and the forcing of impurities to the surface of the metal where they can be readily skimmed off.

From the foregoing it will be apparent that the present furnace provides a highly effective and efficient means for melting metal in a crucible through the use of relatively cheap coke as the fuel. The present construction, therefore, permits the melting of high grade metal at a much lower cost than is possible with other types of furnace constructions.

It is to be understood that the form of the invention herewith shown and described is to be taken as a preferred example of the same and that various changes in the shape, size, and arrangement of parts may be resorted to without departing from the spirit of the invention or the scope of the subjoined claims.

We claim:

1. A crucible furnace comprising a wall structure, a grate within said wall structure, a draft chamber below said grate, said wall structure having a continuous horizontal passage formed therein above the level of said grate and provided with an opening communicating directly with said draft chamber, a preheating chamber surrounding said draft chamber and communicating with said passage solely at a point horizontally remote from said opening, and means for supplying air to said preheating chamber at a point remote from its point of connection with said passage.

2. A crucible furnace comprising a wall structure part of which is made up of an annular lining of fire brick material, a grate within said wall structure, a draft chamber beneath said grate, said wall structure being provided with a pair of horizontal annular passages spaced one above the other and each having its radially inner wall formed by said fire brick material, said wall structure being provided with an inlet opening for the lower of said passages communicating between said passage and said draft chamber, said wall structure being further provided with an inlet opening for the upper of said passages communicating between such passage and the lower passage above said first named opening, said wall structure being further provided with outlet openings remote from said inlet openings, one communicating between the upper and lower of said passages and the other communicating between the lower passage and said draft chamber, and means for supplying air to said first named inlet opening.

3. A crucible furnace comprising a wall structure part of which is made up of an annular lining of fire brick material, a grate within said wall structure, a draft chamber beneath said grate, said wall structure being provided with a pair of horizontal annular passages spaced one above the other and each having its radially inner wall formed by said fire brick material, said wall structure being provided with an inlet opening for the lower of said passages communicating between said passage and said draft chamber, said wall structure being further provided with an inlet opening for the upper of said passages communicating between such passage and the lower passage above said first named opening, said wall structure being further provided with outlet openings remote from said inlet openings, one communicating between the upper and lower of said passages and the other communicating between the lower passage and said draft chamber, and means for supplying air to said first named inlet opening, said second named inlet opening being of a cross-sectional area approximately one-half the cross-sectional area of the first named inlet opening whereby approximately one-half the air passing through said first named opening will flow through each of said passages.

4. A crucible furnace comprising a wall structure part of which is made up of an annular lining of fire brick material, a grate within said wall structure, a draft chamber beneath said grate, said wall structure being provided with a pair of horizontal annular passages spaced one above the other and each having its radially inner wall formed by said fire brick material, said wall structure being provided with an inlet opening for the lower of said passages com-

municating between said passage and said draft chamber, said wall structure being further provided with an inlet opening for the upper of said passages communicating between such passage and the lower passage above said first named opening, said wall structure being further provided with outlet openings remote from said inlet openings, one communicating between the upper and lower of said passages and the other communicating between the lower passage and said draft chamber, a preheating chamber surrounding said draft chamber and communicating with said first named opening, and means for supplying air to said preheating chamber at a point remote from the point of connection of said preheating chamber with said first named opening.

5. A crucible furnace comprising a wall structure part of which is made up of an annular lining of fire brick material, a grate within said wall structure, a draft chamber beneath said grate, a crucible supporting block arranged centrally of said grate and projecting thereabove, said block being provided with upwardly and outwardly diverging openings therethrough communicating at their lower ends with said draft chamber, said wall structure being provided with a pair of horizontal annular passages spaced one above the other and each having its radially inner wall formed by said fire brick material, said wall structure being provided with an inlet opening for the lower of said passages communicating between said passage and said draft chamber, said wall structure being further provided with an inlet opening for the upper of said passages communicating between such passage and the lower passage above said first named opening, said wall structure being further provided with outlet openings remote from said inlet openings, one communicating between the upper and lower of said passages and the other communicating between the lower passage and said draft chamber, and means for supplying air to said first named inlet opening.

6. A crucible furnace comprising a wall structure part of which is made up of an annular lining of fire brick material, a grate within said wall structure, a draft chamber beneath said grate, a crucible supporting block arranged centrally of said grate and projecting thereabove, said block being provided with upwardly and outwardly diverging openings therethrough communicating at their lower ends with said draft chamber, said wall structure being provided with a pair of horizontal annular passages spaced one above the other and each having its radially inner wall formed by said fire brick material, said wall structure being provided with an inlet opening for the lower of said passages communicating between said passage and said draft chamber, said wall structure being further provided with an inlet opening for the upper of said passages communicating between such passage and the lower passage above said first named opening, said wall structure being further provided with outlet openings remote from said inlet openings, one communicating between the upper and lower of said passages and the other communicating between the lower passage and said draft chamber, a preheating chamber surrounding said draft chamber and communicating with said first named opening, and means for supplying air to said preheating chamber at a point remote from the point of connection of

said preheating chamber with said first named opening.

7. A crucible furnace comprising a wall structure, a cylindrical metal jacket surrounding said wall structure and extending therebelow, a grate supported in said wall structure adjacent the lower end thereof, the space within said jacket beneath said grate forming a draft chamber, said wall structure being provided with an annular passage above the level of said grate, said passage being provided at diametrically opposite points with openings one of which is an inlet opening and the other of which is an outlet opening communicating with said draft chamber, a casing surrounding said jacket and forming therewith an annular preheating chamber communicating with said inlet opening, and means for supplying air to said preheating chamber at a point remote from the point of connection of such chamber with said inlet opening.

8. A crucible furnace comprising a cylindrical wall structure at least a portion of the interior of the lower end of which is formed annular of fire brick material, a metal shell surrounding said wall structure and extending therebelow, a shelf structure supported by said shell and on which said wall structure rests, a grate arranged within said wall structure, said shelf extending slightly inwardly radially of said wall structure to support the peripheral portion of said grate, the space within said shell below said shelf forming a draft chamber, said wall structure being provided with a pair of annular passages spaced one above the other and having their radially inner wall surfaces formed by said fire brick material, said wall structure being provided with a pair of inlet openings one of which communicates with the lower passage and the other of which communicates between said passages, said wall structure being further provided with outlet openings one of which communicates between said passages and the other of which communicates between the lower passage and said draft chamber diametrically opposite said inlet openings, and means for supplying air to said first named inlet opening.

9. A crucible furnace comprising a cylindrical wall structure at least a portion of the interior of the lower end of which is formed annular of fire brick material, a metal shell surrounding said wall structure and extending therebelow, a shelf structure supported by said shell and on which said wall structure rests, a grate arranged within said wall structure, said shelf extending slightly inwardly radially of said wall structure to support the peripheral portion of said grate, the space within said shell below said shelf forming a draft chamber, said wall structure being provided with a pair of annular passages spaced one above the other and having their radially inner wall surfaces formed by said fire brick material, said wall structure being provided with a pair of inlet openings one of which communicates with the lower passage and the other of which communicates between said passages, said wall structure being further provided with outlet openings one of which communicates between said passages and the other of which communicates between the lower passage and said draft chamber diametrically opposite said inlet openings, a casing surrounding said shell radially outwardly of said draft chamber and forming with said shell a preheating chamber communicating with said first named inlet opening, and means

for supplying air to said preheating chamber at a point remote from its point of connection with said first named inlet opening.

10. A crucible furnace comprising a cylindrical wall structure, a circular grate arranged within said wall structure adjacent the lower end thereof and provided with a central opening, a draft chamber beneath said grate, said wall structure being provided with an annular passage above the level of said grate and a pair of diametrically opposite openings one of which is an inlet opening and the other of which is an outlet opening communicating between said passage and said draft chamber, a crucible supporting block having its lower end arranged in the opening in said grate, a supporting structure beneath said grate for supporting the latter adjacent the opening therein and for supporting said block, said supporting structure comprising a tubular pedestal having openings communicating with said draft chamber, said block having upwardly and outwardly diverging openings communicating at their upper ends with the space within said wall structure above the grate and at their lower ends with the interior of said tubular pedestal, and means for supplying air to said inlet opening.

11. A crucible furnace comprising a cylindrical wall structure, a circular grate arranged within said wall structure adjacent the lower end thereof and provided with a central opening, a draft chamber beneath said grate, said wall structure being provided with an annular passage above the level of said grate and a pair of diametrically opposite openings one of which is an inlet opening and the other of which is an outlet opening communicating between said passage and said draft chamber, a crucible supporting block having its lower end arranged in the opening in said grate, a supporting structure beneath said grate for supporting the latter adjacent the opening therein and for supporting said block, said supporting structure comprising a tubular pedestal having openings communicating with said draft chamber, said block having upwardly and outwardly diverging openings communicating at their upper ends with the space within said wall structure above the grate and at their lower ends with the interior of said tubular pedestal, a preheating chamber surrounding said draft chamber and communicating with said inlet opening, and means for supplying air to said draft chamber at a point remote from the point of connection of the latter with said inlet opening.

12. A crucible furnace comprising a relatively thick wall structure having a fire brick lining of substantial height within the lower portion thereof and made up of layers of brick laid in annular form, a metal shell surrounding said wall structure and extending therebelow, said wall structure further comprising a pair of rows of vertically spaced bricks each laid in annular form in contact with said shell and having their radially inner faces spaced from said fire bricks to form annular passages, and a plurality of annular rows of brick above, below and between said last named rows of bricks, the bricks of said plurality of rows having their radially inner faces contacting with said fire bricks and their radially outer faces spaced radially inwardly of said shell, a cementitious mixture filling the spaces between said shell and the radially outer faces of the bricks of said plurality of rows, said wall structure having diametrically opposite

openings communicating between said passages, a grate arranged within the lower row of fire bricks, a draft chamber formed beneath said grate, said wall structure having diametrically opposite inlet and outlet openings the latter of which communicates between the lower annular passage and said draft chamber, and means for supplying air to said inlet openings.

13. A crucible furnace comprising a wall structure part of which is made up of an annular lining of fire-brick material, a grate within said lining, a draft chamber below said grate, said

10

lining having a continuous horizontal passage formed therein above the level of said grate and provided with an opening communicating with said draft chamber, a preheating chamber surrounding said draft chamber and communicating with said passage at a point remote from said opening, and means for supplying air to said preheating chamber at a point remote from its point of connection with said passage.
